UNITED STATES PATENT OFFICE.

GEORGE P. BAILEY, OF ROCHESTER, NEW YORK.

STENCIL-FRAME.

SPECIFICATION forming part of Letters Patent No. 351,149, dated October 19, 1886.

Application filed July 8, 1886. Serial No. 207,453. (Model.)

To all whom it may concern:

Be it known that I, GEORGE P. BAILEY, of Rochester, in the county of Monroe and State of New York, have invented certain new and useful Improvements in Stencil-Frames; and I do hereby declare the following to be a full, clear, and exact description of the same, reference being had to the accompanying drawings, forming a part of this specification, and to the figures and letters of reference marked thereon.

My invention relates to that class of stencils in which movable letters are used in connection with a frame or holder; and it consists, first, in a novel construction of the individual letter-plates, and, secondly, in the combination of such letter-plates with a frame or holder adapted especially to receive them, all as will be hereinafter fully described.

Referring to the accompanying drawings, Figure 1 represents a top plan view of a stencil constructed in accordance with my invention. Fig. 2 is a sectional view taken on the line *xx*, Fig. 1; Fig. 3, a view taken on the line *yy*, Fig. 1; Fig. 4, a perspective view of one of the letters detached; Figs. 5 and 6, views showing different ways of holding the letters that are not in use; Figs. 7 and 8, cross-sectional views taken on the lines *zz* and *ww* of Figs. 5 and 6 respectively.

Similar letters of reference in the several figures indicate the same parts.

The letter A indicates the frame or holder, and B the individual letter-plates employed in my improved stencil. The frame A consists, preferably, of a rectangular plate of spring brass or steel, having a rectangular opening, C, extending longitudinally of it, as shown. Each of the letter-plates consists of a piece of thin metal having stamped or cut from it a letter or character, and having its ends turned backward, so as to form ears b, which stand slightly off from the body, as shown in Figs. 3 and 4, and serve, first, as a means for maintaining a connection with the frame or holder A when the plates are slid upon the latter, and, secondly, as a means for preventing contact between the inked face of one plate and the uninked back of the adjoining plate when two or more plates are assembled in racks or brackets, such as shown in Figs.

5 and 7, and Figs. 6 and 8, respectively. The ears b are formed upon these letter-plates with great accuracy, and preferably by machinery, and the frame or holder with 55 which they co-operate is also accurately formed, so that when the plates are slipped upon the frame and assembled the proximate edges of said plates will abut closely together without overlapping in the slightest, while 60 both their fronts and backs will present smooth and unbroken surfaces, the latter resting directly and closely upon the surface to be marked, and the former offering no obstruction to the inking-brush as it is swept from end to end of 65 the frame in the practical use of the device.

Upon one end of the frame or holder is permanently secured a stop consisting, preferably, of a band, E, the function of which is to prevent the plates being slipped entirely off the 7c frame, while at the opposite end of the frame a follower, G, is adapted to be applied, its function being to prevent lateral motion of the plates after they have been properly assembled.

A handle, H, such as shown in Figs. 1 and 75 2, is preferably applied to the frame for convenience in manipulating the stencil.

The letter-plates when not in use upon the frame are preferable hung upon the pins P of a rack, R, such as shown in Figs. 5 and 7, or 80 deposited in the compartments K of a receptacle, S, as shown in Figs. 6 and 8; but whether arranged in either of these ways, or in any other manner involving their superposition, contact between the proximate faces and backs 85 of adjacent plates is prevented by the flanges b, as before explained.

Having thus described my invention, what I claim as new is—

1. The herein-described letter-plate for a 90 stencil having a character cut or formed therein, and having its opposite ends bent backward so as to form raised flanges on one side of the plate, as and for the purpose set forth.

2. In a stencil, the combination, with the 95 frame or holder, consisting of a rectangular plate, such as described, having a longitudinal opening, of the letter-plates having their ends turned backward so as to form flanges which are adapted to embrace the edges of the frame, 100 as and for the purpose set forth.

3. In the herein-described stencil, the com-

bination of the rectangular frame having a longitudinal opening and the permanent stop at one end, of the letter-plates having their ends turned back so as to form flanges and the 5 follower for maintaining the assembled letter-plates in position, as set forth.

4. In a stencil, the combination, with the

letter-plates, of a rack or holder, substantially as described, for keeping said plates assorted and in order when not in use, as set forth.

GEORGE P. BAILEY.
